[57] CLAIM

The ornamental design for a lavatory, as shown and described.

DESCRIPTION

FIG. 1 is a right side elevational view of a lavatory showing my new design, the left side being a mirror image of the right side;

FIG. 2 is a top plan view thereof;

FIG. 3 is a front elevational view thereof;

FIG. 4 is a rear elevational view thereof;

FIG. 5 is a bottom plan view thereof; and
FIG. 6 is a cross sectional view taken on line VI—VI of FIG. 3.
